UNITED STATES PATENT OFFICE.

FRANCIS P. KANE, OF JACKSONVILLE, ILLINOIS.

HAND BAG.

Application filed November 20, 1922. Serial No. 602,140.

To all whom it may concern:

Be it known that I, FRANCIS P. KANE, residing at Jacksonville, Illinois, a citizen of the United States, have invented certain new and useful Improvements in Hand Bags, of which the following is a specification.

My invention relates to so called shopping bags which as ordinarily made have a pouch or sack of considerable size in order that the bag may have an adequate capacity for holding articles, and my object is to so construct such a bag that when not in use it may be reduced to a very compact state so that it will have neither the bulk nor the appearance of the shopping bag and thus will be neat or attractive in appearance and readily handled or carried. My invention consists in any bag having the characteristics of construction and adaptability described by or included within the language of the appended claims.

In the accompanying drawings:

Fig. 1 is a perspective view of a bag embodying my invention opened out for use as a shopping bag;

Fig. 2 is a similar view showing the bag in its folded or compacted condition;

Fig. 3 is a section on the line 3—3 of Fig.

In the embodiment of my invention appearing in the drawings, the design or idea is to have the bag in its compact state to present the appearance and size of an attractive looking hand-bag, and in the bag shown in the drawings the pouch or sack, 10, when opened out as shown in Fig. 1 tapers from top to bottom so that it has the appearance of an inverted keystone and at the narrow top or mouth of the bag there are on opposite sides two loops, 11, that form handles which may be caught hold of by the hand or slipped over the arm. A bellows fold, 12, is used at each side of the sack which enables the sack or pouch when not in use to be closed up in a flat condition while giving ample holding capacity to the bag when it is opened out.

When, as is illustrated in Fig. 2, the bag is to be given the appearance of a small hand

bag, the lower half is folded or doubled over against the upper half, the bottom edge of the sack or pouch being brought up substantially to the level, or a little below the level of the bag top or mouth, and it is there secured, but preliminary to thus turning or folding it over, the two corners of the pouch bottom are folded over each in a triangular fold so as to make the bottom edge or mouth of the bag, the result being that the contour and area of the thus folded-over lower half of the bag matches the contour and area of the other half, the folded corners being turned inward so that they are concealed and, hence, the bulk of the bag is reduced to practically one-half and it presents the neat and attractive appearance of a hand-bag. In Fig. 1 the dotted line, $x-x$, indicates the line on which the lower half is folded, and the dotted lines, $x-y$, indicates the lines of fold of the lower corners of the sack or pouch, and, preferably, in the manufacture of the bag there is a more or less defined crease produced along such three lines to indicate to the user the places where folds are to be made and to facilitate such folding. These creases, however, are not sufficiently marked so as to in anywise impair the appearance of the bag when fully opened out. A snap button, 13, may be used to hold the corners but it is not claimed as my invention.

When folded as I have explained, the overlapping portions of the bag are retained in the folded state by suitable means. Such means, as shown in the drawings, comprises a flap, 14, which is secured at one edge to the top of the pouch or sack and is adapted to lap over the outside of the upper part of the folded-over bottom half of the pouch and to be detachably secured thereto by a snap button, whose members, 15, and 16 are, respectively, attached to the two parts concerned. The flap, 14, is utilized to form a coin purse which has a closure-forming flap, 17, to secure which a snap button, 18, is provided. By the provision of the purse the appearance of the article as a hand bag is contributed to and the purse is most conveniently located for ready access.

The bellows-fold, or accordion pleat, 12, is widest at the top or mouth of the opened out bag, and tapers to substantially no width at the bottom, and the bag both when unfolded and folded being of trapezoidal shape with the trapezoidal base at the bottom, and when the lower corners are folded in the shape is bi-trapezoidal. The bag is formed of a substantially rectangular piece of material that is folded at the transverse center, and its opposite edges are folded inward and stitched to form the tapering accordion plaits.

Bags embodying my invention may be made of leather or other material, and while the design and details of construction and arrangement of the bag appearing in the drawings make a most satisfactory embodiment of my invention, I do not confine myself thereto.

What I claim is:

1. A bag having a pouch that tapers and being widest at the bottom and having a handle at the top and foldable on a line midway between top and bottom, the corners at the bottom being foldable to lie upon adjacent portions of the pouch, each corner being foldable upon a line that intersects the outer edge of the bag at the point where it is folded midway between top and bottom and means to hold the folded over portions in overlying relation.

2. A bag having a pouch that tapers, it being widest at the bottom and having a handle at the top, the pouch having a bellows fold at each of two sides, and foldable on a line midway between top and bottom, the corners at the bottom being foldable to lie upon adjacent portions of the pouch, and means to hold the folded over portions in overlying relation, comprising a purse-forming flap attached at one edge to the top of the pouch.

3. A shopping bag comprising a piece of material of elongated, substantially rectangular shape folded at its transverse center and having its adjacent side edges secured together and folded inwardly into triangular accordion plaits to form an open-ended trapezoidal shape with the base of the trapezoid at the bottom, said plates being wider at the top than at the bottom, and a pair of handles secured to the upper sides thereof.

4. A shopping bag comprising a piece of material of elongated, substantially rectangular shape folded at its transverse center and having its adjacent side edges secured together and folded inwardly into triangular accordion plaits to form an open-ended trapezoidal shape with the base of the trapezoid at the bottom, a fastening member disposed centrally of the bag at one side thereof adjacent its upper edge, a complementary fastening secured centrally

of said side adjacent the bottom edge, the lower corners of the bag being folded inwardly and the bag then folded substantially along its transverse center and held in such folded position by the engagement of said fasteners.

5. A carrying bag comprising an open-ended elongated receptacle of substantially trapezoidal shape in elevation formed by having its sides folded inwardly in triangular accordion plaits, said plaits being of appreciable width at the top of the bag, but tapering to substantially no width at the bottom thereof, the space between said plates being wider at the bottom than at the top, a fastening member disposed at the transverse center of the bag at one side thereof adjacent its bottom and a complementary fastening member secured substantially at the transverse center of the bag adjacent the top thereof, whereby the bottom of the bag can be folded upwardly along an intermediate transverse line, and the upwardly folded portion be held in position by engagement of said fastening members.

6. A carrying bag comprising an open-ended, elongated receptacle of substantially trapezoidal shape in elevation, formed by having its sides folded inwardly in triangular accordion plaits said plaits being of appreciable width at the top of the bag, but tapering to substantially no width at the bottom thereof, the space between said plaits being wider at the bottom than at the top, a fastening member disposed at the transverse center of the bag at one side thereof, adjacent its bottom, a complementary fastening member secured substantially at the transverse center of the bag adjacent the top thereof, whereby the bottom of the bag can be folded upwardly along an intermediate transverse line and the upwardly folded portion be held in position by engagement of said fastening members, and a pocket member secured along its upper edge to one side of the bag adjacent the top edge thereof and adapted to depend so as to overlap and cover the upwardly folded bottom of the bag.

7. A shopping bag having an open-ended and substantially rectangular body when fully distended, but having its sides folded inwardly in accordion plaits which are wide at the top but taper to a narrow width at the bottom, the space between said plaits being wider at the bottom than at the top, whereby the bag would have a trapezoidal shape, said bag adapted to have its lower corners folded inwardly in triangular folds whereby a bi-trapezoidal shape is formed, and to have its bottom portion then folded upwardly along a transverse line with its lower edge disposed some distance below the top edge, whereby a smaller trape-

zoidal shape is produced, and co-operating fastening means on the bag to hold the same in its folded position.

8. In a combination carrying bag, a bag body, a purse having a closing flap, fastened only along its upper edge on one side of the bag along the edge to the opening of the bag, the bag being foldable upon itself

underneath the purse, and means permanently located between the bag and purse 10 cooperating with other means on the bag body for fastening the bag in such folded position.

In testimony whereof I hereunto affix my signature.

FRANCIS P. KANE.
